UNITED STATES PATENT OFFICE.

MAURICE TAUSSIG, OF CHICAGO, ILLINOIS.-

DESIGN FOR A LEG FOR STORE FURNITURE.

47,937.

Specification for Design.

Patented Oct. 5, 1915.

Application filed June 30, 1915. Serial No. 37,386. Term of patent 3½ years.

To all whom it may concern:

Be it known that I, MAURICE TAUSSIG, a citizen of the United States, residing at Chicago, in the county of Cook and State of Illinois, have invented a new, original, and ornamental Design for a Leg for Store Furniture, of which the following is the specification, reference being had to the accompanying drawing, forming part thereof.

In said drawing, Figure 1 is a perspective view of a leg for store furniture, showing my design; and Fig. 2 is an end view, looking at the bottom of the leg.

I claim:

The ornamental design for a leg for store furniture, as shown.

MAURICE TAUSSIG.
